CHRISTEN CHRISTENSEN, OF CHICAGO, ILLINOIS, ASSIGNOR TO ELECTRICAL ENGINEERS EQUIPMENT CO., OF CHICAGO, ILLINOIS, A CORPORATION OF ILLINOIS

SWITCH-LOCKING MECHANISM

Application filed August 17, 1925. Serial No. 50,540.

The present invention relates in general to electrical switches and more particularly to improvements in electrical switch locking mechanism.

5 My improvements have particular reference to switches employed in connection with high tension transmission service, such as, for example, disconnecting switches. Disconnecting switches are adapted to function 10 as auxiliary switching elements, as is well known to those versatile with the present art, and to operate in conjunction with any switching device of high power interrupting capacity.

15 In transmission installations such as power house and sub-station installations, it is the general practice to use a disconnecting switch in the line immediately before the typical oil circuit breaker. Also, quite commonly, a disconnecting switch is employed in the line 20 leading from the circuit breaker intermediate the breaker and the omnibus bar. The duty of initially interrupting the current flow is performed by the oil circuit breaker, 25 whereas the function of the disconnecting switch is to thereafter open the line where it enters the station and to thus disconnect 30 all of the station apparatus, including the circuit breaker from the line. This, as is obvious, enables repair and adjustment of the circuit breaker and other station apparatus to be performed without danger of injury from the line potential.

I have found, in practice, that the ordinary 35 types of switch locking mechanism do not function properly when the switch is subjected to stresses and strains. This is particularly true of high tension switches or switches designed for outdoor installation 40 and switches which employ long insulator pillars. In the case of switches employing long insulator pillars, there is quite a considerable amount of deflection or spring between the terminals of the switch. I propose, in 45 accordance with the features of the present invention, to provide a high tension switch locking mechanism which will remain positive and reliable in operation even under a relatively large deflection of the insulators 50 and switch terminals.

In practice, I was confronted with the problem of providing suitable and reliable locking mechanism for switches having a plurality of switch units such as multiple single pole, single throw, gang operated 55 switches. I have reference generally to switches such as that disclosed in my co-pending application, Serial No. 646,750, filed June 21st, 1923, now Patent No. 1,584,732, May 18, 1926. Due to the play existant between the switch units, I found it impracticable to employ locking mechanism connected to the switch blades of all the units. Moreover, it was far more desirable to provide locking mechanism associated with one 60 switch unit, adapted to not only lock the unit in its closed position, but to also contemporaneously cause all of the other units to be locked in their closed positions.

65 I propose, in accordance with other features of the present invention, to provide a switch having a plurality of switch units, wherein one of the switch units is provided with locking mechanism, adapted to contemporaneously lock all of the switch units in 70 their closed positions.

An object of the present invention is to provide improved switch locking mechanism.

Another object of the present invention is to provide a switch having a plurality of 80 switch units wherein one lock suffices to lock all of the units thereof.

Other objects and advantages of the present invention will more fully appear from the following detailed description taken in 85 connection with the accompanying drawings, which illustrate one embodiment thereof, and in which:

Figure 1 is a front elevation of a plurality of switch units embodied with the features 90 of the present invention;

Figure 2 is a side view of the structure shown in Figure 1;

Figure 3 is an enlarged elevation of the locking mechanism as shown in Figure 1; 95

Figure 4 is a side view of the locking mechanism shown in Figure 3;

Figure 5 is a sectional view taken on a line 5-5 of Figure 3 looking in the direction indicated by the arrows; 100

Figure 6 is a sectional view taken on a line 6—6 of Figure 5, and

Figure 7 is a fragmentary view of a modified form of switch blade.

Referring now to the drawing in detail, in which like reference numerals designate similar parts throughout the several views, 10 denotes a base or supporting frame upon which the switch is erected and which may be of any conventional form. The base 10 may be mounted on pole tops, switching towers, or in any other desired location. The switch I have illustrated, comprises three switch units and in practice is commonly termed a three single pole single throw gang operated switch. It is, of course, to be understood that my invention is not to be limited to the number of units shown nor to the number of poles in each unit.

All of the three units are identical in construction with the exception that the middle unit has, mounted thereon, my improved locking mechanism. Therefore, a description of one of the units will suffice for all of them.

Each unit comprises a pair of suitable insulators 11 and 12 which may be attached to the base 10 in any desirable manner. The free end of the insulator 12 carries the hinge terminal 13 to which the switch blade 14 is pivoted and the free end of the insulator 11 carries the contact terminal 15. Each terminal has, extending therefrom, a connecting lug or clip 16 to which are connected the opposite sides of the line (not shown).

The switch blade 14 comprises two spaced blades 14' engaging its pivot on opposite sides of the hinge terminal 13. A pivot bolt 17 passes through the switch blades and through the hinge terminal. The hinge terminal is provided with the usual spring washers 18 which function to normally urge the switch blades into firm contact with the sides of the terminal 13. The other end of the switch blade 14 has, passing therethrough, a pair of bolts 19 and 20, one on each side of the terminal 15 which are also provided with spring washers 21. These spring washers function to draw the blades 14' together, thus enabling the blades to fit tightly on the terminal 15, and causing the switch blades to form a contact with the sides of the terminal 15.

Located intermediate the ends of the switch blades 14 is a pivot bolt 22 to which one end of an element or link 23 is pivoted. The pivoted end of the link 23 preferably projects intermediate the blades 14'. Mounted on the pivot bolt 22 are the usual spring washers 24, one on each side of the blades. The link 23 passes through a suitable aperture in the base 10 and is pivotally attached at its other end to the free end of an arm 25, attached to a shaft 26. The shaft 26 is shown as being of a square cross-section and is journaled in suitable bracket elements 27

carried by the base or frame 10. The arm 25 of each unit may be rigidly attached to the shaft 26, being held in place thereon by any suitable means, as for an example, a set screw, not shown. Also, the aperture in the arm 25 for receiving the shaft 26 may be a little larger than the shaft, so as to permit adjustment thereon. That is to say, quite frequently one switch becomes a little loose with respect to the other switch units and it is necessary to tighten it up in order for it to work in harmony with the other units. This adjustment may be made if the arm 25 is not rigidly attached to the shaft 26.

The arm 25 of each switch unit is mounted on the shaft 26, which is common to all units. Therefore, by operating one switch blade about its hinge-terminal, it must necessarily follow that the switch blades of the other units must be contemporaneously operated. Obviously, by locking one of the units, it would result in all of the other units being also locked. I shall now proceed to describe in detail my novel locking mechanism.

My novel lock which is designated generally by the reference numeral 30 is shown mounted on the middle switch unit, in Figure 1. It is to be understood, however, that this lock may, with equal advantage, be mounted on any of the three units illustrated, the result accomplished, however, being the same. The lock device to be hereinafter described in detail is of the same species as that disclosed in my co-pending application, Serial No. 656,442, filed August 8, 1923, now Patent No. 1,720,818, July 16, 1929. It is my intention to cover the broad aspect of my locking mechanism in the aforesaid co-pending application and to cover certain specific novel features disclosed in the present application by the claims of this case.

Lock 30 comprises a pair of guides or horns 31 (Figs. 3 and 5), one being disposed, on each side of the contact terminal 14, and extending upwardly from the head of the associated insulator. The space separating the horn, or in other words, the throat, therebetween, is immediately above the contact terminal 15 and is preferably substantially in alignment therewith. This construction is desirable inasmuch as it enables the horns or guides to properly guide the two switch blades 14—14' of the switch blade 14 down on opposite sides of the terminal 15. Each guiding horn includes a curved rear or outer wall 33 and two forwardly extending side walls 34 which form vertical rectangular recesses 35 in the opening faces of the guiding horns for receiving detent members 36. Extending upwardly from the recess portion 35 is a curved horn consisting of a front web 37 having a reinforcing rib or flange 38 extending backwardly along each edge of the web 37. The upper part of the contact terminal 15

is reduced in thickness to form slots on each side between the terminal and opposing faces of the guiding horn 31 for receiving the switch blades 14'-14'. The scarfed-out sides 5 of the terminal leave shoulders 39 (Figure 5), which form positive stops for the inward movement of the switch blades 14'-14'. The thicker portion below the shoulders 39 is formed with a horizontal base 41 mounted on 10 and attached to the terminal bracket or head 42 carried on the upper end of the insulator 11. The lower ends of each guiding horn 31 are placed in contact with the sides of the widened portion of the contact terminal and 15 these horns are each formed with a cross web or bar 43 for enabling them to be bolted to the terminal base 41. Bolts 44 are used for this purpose. These bolts, as desired, may also serve the additional function of securing 20 the terminal base 41 to the mounting head 42.

The detent or locking function is performed by the two detent members 36-36 which are mounted for pivotal motion in the 25 rectangular recesses or pockets 35-35, the upper ends of these detent members having inwardly extending jaws 46, which are adapted to hook over the upper longitudinal edges of the blades 14'-14'.

From the jaws 46, the detent members are curved backwardly to form guiding horns 47, by which the switch blades 14'-14' are guided over the terminal 15 and the detent members are cammed apart for permitting 30 the engagement of the switch blades with the terminal. The detent members 36 are pivotally supported at their lower ends by providing pivot pins or studs 48, extending from each edge of the detent member in a 35 plane parallel to the switch blades. These pivot pins or studs are suitably carried by the lower portion of the guiding horns 31-31.

Each detent member is preferably urged 40 against its respective blade member 14' by a suitable spring or resilient mechanism whereby an intimate firm contact is maintained between the blades 14' and terminal 15 and also between the blades and the detent members.

This spring mechanism may consist of 45 springs arranged singly or in duplicate to apply a resilient pressure to the back of each detent member at one or more points. In the embodiment illustrated in the drawing, only one spring is associated with each detent member. In the arrangement shown 50 the spring 51 bears, at one end, against the inner wall of the associated horn 31 and at its other end against the back of the horn portion of the detent member 36. A cup 55 portion 52 is formed on the inner wall of the horn 31 for receiving the end of the spring. If it is so desired, means may be provided for adjusting the tension of the spring. Such a means is illustrated in my co-pending 60 application, Serial No. 656,442 now Pat-

ent No. 1,720,818, July 16, 1929, previously mentioned.

It will be observed that by locating the two jaws 36 in the same transverse plane as the contact terminal 15 and applying spring 70 pressure to the outer sides of these jaws acting inwardly against the switch blades, these jaws perform the secondary function of firmly pressing the switch blades into intimate contact with the contact terminal for 75 effective electrical connection therewith, in addition to their primary function of locking or restraining the switch blades. Also, the jaws or detent members 36 may operate as a friction or spring lock, or as a positive lock, 80 depending upon the requirements of the situation. In the previously mentioned co-pending application, I have illustrated both forms of locking mechanism. In the present embodiment, only a positive lock is illustrated. 85

When a positive lock is provided, obviously, means must be furnished for releasing this positive lock before the switch blades can be withdrawn. An exemplary form of 90 this releasing means is illustrated in Figures 3 and 4. I have found that the form illustrated is not only highly advantageous, but is both efficient and practical in use. Before proceeding to describe this releasing mechanism, it should be noted that the jaws 46-46 are cut at right angles to the plane of the terminal 15 (Figure 5), so as to hook over the outer edges of the switch blades 14'-14' and positively lock the switch blades in 95 against the contacting terminal.

The novel releasing means consists of a lock releasing member 61 which is pivoted on a bolt 62 passing through both of the blades 14', adjacent their outer ends. A pivot lug 63 extends down from the releasing member 61 between the switch blades and receives the pivot bolt 62. A ring 64 extends from the outer end of the switch releasing 100 member 61 for receiving the hook on the end of the usual operating pole. The lock releasing member 61 is provided with a projection 65 which has the lateral projection 66 adapted to be moved between the horns 31-31.

The projection 66 comprises the separating member and when it is forced down between the curved horns 47 it is adapted to cam the detent members 36 apart, thereby releasing the jaws 46 from the top of the blades 14'-14', permitting the latter to be withdrawn from their contact with the terminal 15. This will follow as a natural sequence, resulting from an upward or outward pull exerted on the ring 64 through the usual switch operating pole. The initial effort 110 will force the projection 65 down between the curved horn 47 so as to separate the locking jaws after which the continuous pull on the pole will draw the switch blades out over the end of the contact terminal 15.

Another feature of my invention is con- 115

cerned with the lug 63 of the releasing member 61. This lug is provided with a projection 70 which constitutes a stop. This stop is adapted to engage the bolts 20 intermediate the blades 14' and to thereby limit the movement of the releasing member away from the horns 31.

This stop or projection 70 is a new feature of my novel lock and is not disclosed in the aforementioned co-pending application. It is highly advantageous since it prevents the lock releasing member from being moved about its pivot into engagement with the lug 16 connected to the transmission line.

From the foregoing description, it is evident that when one of the switch units of the gang or group composing the switch proper is locked in a closed position by my novel locking mechanism, all the other units, in the switch must necessarily also be locked in a closed position, since they are all connected to a common shaft 26. Upon pulling the ring 64 of the lock 30 downwardly with a switch operating pole or some other analogous or suitable means, not only is the middle unit unlocked, but all of the other units are unlocked. Also, by continuing to pull the ring 64, not only will the blade associated therewith be pivoted about its hinged terminal into an open position, but all of the other blades of the switch will be moved similarly. Thus I have provided a simple compact and highly advantageous switch locking mechanism which involves far less effort in its operation than similar switches as heretofore; one lock serving to lock a plurality of units in a switch.

In Fig. 7, I have illustrated a switch blade similar to the one illustrated in the adjacent Fig. 2, with the exception that my novel lock mechanism 30 and the lock releasing member 11 are omitted. The blade is provided with an aperture 90 near its upper end for receiving the end of a pole hook or the like. Obviously, when each switch unit has a switch blade with such an aperture, it is possible to open all of the units contemporaneously by inserting the pole hook in the aperture 90 of one of the blades and pulling the pole downwardly. This action is possible only due to the fact that all of the switch units are associated with a common operating shaft 26.

The present invention is not to be limited by the above description of my preferred embodiment of the invention but only in so far as defined by the scope and spirit of the appended claims.

I claim:

1. In combination, a plurality of switch units, a common support for the said units, each unit comprising a switch element having two blades and a terminal disposed intermediate the two blades when the switch element is in contact therewith, and locking mechanism associated with the said element

of only one of the units for locking all of the units against operation, the said locking mechanism including means for locking the blades associated therewith to the terminal and for urging the blades into tighter engagement with the terminal disposed therebetween.

2. In combination, a plurality of switch units, a common support for the said units, each unit comprising a switch element having two blades and a terminal disposed intermediate the two blades when the switch element is in contact therewith, locking mechanism associated with the said element of only one of the units for locking all of the units against operation, the said locking mechanism including means for locking the blades associated therewith to the terminal and for urging the blades into tighter engagement with the terminal disposed therebetween, means for releasing the said locking mechanism to permit the switch element to be moved away from the terminal, and means carried by the switch element associated with the locking mechanism for urging the blades towards each other and into engagement with the terminal, said latter means being located in the path of movement of the releasing means thereby serving as a stop for limiting the movement of the releasing means.

3. In combination, a switch element comprising two blades, a terminal disposed intermediate the two blades when the switch element is in contact therewith, resilient means for urging the two blades inwardly into engagement with the terminal, means for locking the said element in engagement with the terminal and releasing means for rendering the said locking means ineffective and for permitting the said element to be moved out of cooperation with the said terminal, the said resilient means being located in the path of movement of the releasing means thereby serving to limit the movement of the said releasing means.

4. In combination, a switch element comprising two blades, a terminal disposed intermediate the two blades when the switch element is in contact therewith, means for urging the two blades toward each other and into engagement with the terminal, a lock for locking the said element to the terminal and means for releasing the lock to permit the element to be moved away from the terminal, the said urging means being located in the path of movement of the releasing means thereby serving as a stop for limiting the movement of the releasing means.

5. In combination, a switch element comprising two blades, a terminal disposed intermediate the two blades when the switch element is in contact therewith, spring washer mechanism for urging the blades toward each other and into engagement with the terminal, a lock for locking the switch element

in engagement with the terminal, and means for releasing the said lock to permit the switch element to be moved away from the said terminal, the said spring washer mechanism being located in the path of movement of the releasing means thereby serving to limit the movement of the resilient means.

6. In combination, a switch comprising a plurality of units, each of which includes a switch blade, a common support for said units, each of said units being adapted to accommodate a different phase current and being spaced a predetermined distance from each of the other units, common connecting means for said units spaced from said blades, and a combination operating and lock construction, associated with only one of said units and connected to the blade thereof for contemporaneously locking all of the units against operation through said connecting means, said operating construction being movable to actuate the associated blade and said connecting means causing the other units to move in unison therewith.

7. In combination, a switch comprising three switch units, each of which includes a switch blade, common connecting means for said units spaced from said blades, and a combination operating and lock construction connected only to the blade of the middle unit for contemporaneously locking all of the units against operation through said connecting means, said operating construction being movable to actuate the blade of the middle unit and said connecting means causing the units to move in unison therewith.

8. In combination, a grounded supporting frame, a plurality of pairs of insulators mounted on the front of the frame, switch terminals mounted on said insulators, switch blades pivoted on certain of said terminals and contacting with the remainder of said terminals, operating rods pivoted to said blades between the corresponding terminals of each blade, a rocking shaft having bearings back of said frame arms mounted on the shaft and pivoted to said rods, said rod arms and shaft being connected together for common operation, locking means for locking one of said blades to the corresponding free terminal, and a lock releasing and switch operating eye carried by said one blade.

9. In combination, a grounded supporting frame, a plurality of pairs of insulators mounted on the front of the frame, switch terminals mounted on said insulators, switch blades pivoted on certain of said terminals and contacting with the remainder of said terminals, operating rods pivoted to said blades between the corresponding terminals of each blade, a rocking shaft having bearings back of said frame, arms mounted on the shaft and pivoted to said rods, said rod arms and shaft being connected together for common operation, locking means for locking one

of said blades to the corresponding free terminal, and a switch operating eye carried by one of said blades only for opening and closing all the blades in unison.

10. In combination, a switch comprising a plurality of switch units, a common support for said units, locking means associated with only one of the units for locking all the other units against operation, said locking means including a release member and means effective upon a continued movement of the release member for actuating the switch unit, and a link mechanism connecting all of the switch units whereby the switches move in unison upon the actuation of one of the units.

In witness whereof, I hereunto subscribe my name this 14th day of August, 1925.

CHRISTEN CHRISTENSEN.
